GUN MOUNTING SYSTEM FOR TURRETS

John A. Vaughan, Hempstead, N. Y., assignor, by
mesne assignments, to The W. L. Maxson Cor-
poration, New York, N. Y., a corporation of
New York

Application October 2, 1942, Serial No. 460,491

4 Claims.

(Cl. 89—37)

This invention relates to gun mountings and particularly to a mounting system suitable for use in anti-aircraft gun turrets.

When firing at hostile aircraft the gunner must be able to shift the gun rapidly and accurately in both horizontal and vertical directions and must move his head accordingly in order to remain at all times in proper sighting position. This operation frequently requires considerable contortion of the gunner's neck and body as the gun is swung to follow a plane flying over the gunner. These contortions increase the difficulty of accurate fire.

A general purpose of the invention is to provide a gun mounting in which the gunner can shift the gun rapidly and accurately in any direction above the horizontal and maintain his head in proper aiming relationship to the gun without requiring him to move except for a rocking movement of his head backward or forward within the natural and comfortable range of such head movement. This purpose is in general accomplished by employing a gun pivoted about a horizontal as well as a vertical axis, thereby permitting universal movement of the gun, and supporting the gunner so that the upper end of his spine, which forms a pivot on which his head rocks, is located substantially on said horizontal axis of gun movement. By rotating both the gunner and the gun about the vertical axis, as is usual in gun turret operation, the gunner can maintain his sighting eye in alignment with the gun sights at all times simply by rocking his head backward or forward about its pivot as the gun is elevated or depressed.

Another purpose of the invention is to locate and support the gunner so that he can comfortably and conveniently rock his head vertically through at least the angle of 90° between horizontal and vertical gun positions. Since the distance that the gunner's head can be comfortably rocked backward, though varying with individuals, is substantially short of 90°, it has heretofore been the practice either to allow the gunner considerable freedom of body movement sufficient to permit him to fire in various upward directions, or to provide a movable seat. Both of these arrangements have obvious disadvantages, the former being awkward while the latter involves considerable mechanical complications including compensation for the body movements of the gunner.

The last mentioned purpose is in general accomplished by providing a seat in which the gunner reclines at an angle to the horizontal which

permits him to look directly upward or horizontally forward without transverse shifting of or strain on the neck, the head being rocked within comfortable limits about its spinal pivot. A seat inclined at about 45° has been found to be suitable for this purpose.

A further object of the invention is to provide an inclined seat of the indicated type which is suitable for supporting men of different proportions comfortably with their heads located accurately in the proper position above indicated. This is in general accomplished by forming the seat of a strip of longitudinally flexible material constituting both the back and the bottom of the seat and supported at its ends. With this type of seat a gunner can locate his head in proper gun sighting position by adjusting himself longitudinally on the seat, and will then be supported comfortably in such position. Moreover, a seat of this type allows great freedom of movement under emergency conditions.

Further objects and advantages will appear from the following description considered in connection with the accompanying drawing in which Fig. 1 is a diagrammatic side elevation of a gun mounting, including the turret support and operator's seat, with parts broken away, showing the gun in horizontal position;

Fig. 2 is a similar view with the gun in vertical position; and

Fig. 3 is a fragmentary section on line 3—3 of Fig. 1 showing the mounting of the gun trunnion.

The invention is illustrated in its application to a gun turret of the type in which the gun is mounted for vertical movement, the combination of such movement with the required rotation of the turret serving to aim the gun at any desired point on or above the horizontal. The construction includes a base 10 on which a turret platform 11 is rotatably mounted by means of rollers 12 on track 13 or in any other well known manner. Mounted on platform 11 is a suitable seat for the gunner, indicated generally at 14, and one or more guns 15, which may be machine guns or cannon. An arrangement suitable for the use of guns on either side of the gunner is shown, each gun or group of guns being supported by brackets 16 and pivotally mounted within a trunnion frame 17 on platform 11 so that each gun 15 is rotatable about a horizontal axis passing through the cranial pivot 19 of a gunner 22 in seat 14, said pivot being located in the articulation between the occipital bone 20 and the first cervical vertebra 21 of the gunner.

Various types of trunnion construction may be employed. In the form shown the brackets 16 are attached to a trunnion member such as metal disk 23 movable on ball bearings 23a along a circular track 24 carried by frame 17. Connected to disk 23 is the sighting device 25 of any desired type extending into alignment with the eyes of the gunner 22 and movable with the guns 15.

It will be understood that a corresponding gun support may be located on the near side of the gunner, so that he can operate a plurality of guns simultaneously, in accordance with well known turret construction, the near gun mount being broken away in the interest of clearness.

The trunnion disk 23 and turret platform 11 may be rotated in any desired manner, either manually or by electric drives of known types, which therefore are not illustrated, a reversible electric drive motor 26 mounted on frame 17 and geared to a drive sector 27 attached to disk 23 being illustrated as representative of one type of electrical gun elevating means. These controls, as well as the firing button for the guns, are ordinarily operated from one or more control handles 28 carried by bracket 29 extending from platform 11 into convenient position for operation by the gunner 22.

In order to permit the gunner 22 to tilt his head vertically about its pivot 19 between horizontal sighting position as shown in Fig. 1 and vertical sighting position illustrated in Fig. 2, without the strain and difficulty in maintaining head alignment with the sights that results from tilting the head backward to an excessive extent, the seat 14 is located and arranged so that the operator's back is inclined to the horizontal sufficiently to bring the vertical firing position of his head within the range of easy backward movement of the head about its pivot 19. Since the operator's head can readily be tilted forward comfortably from this position into horizontal firing position shown in Fig. 1, this arrangement prevents any tendency for the operator to shift his neck relative to the trunnion axis 18, a tendency that would have to be counteracted by muscular effort on the part of the gunner, resulting in strain and less effective sighting under emergency conditions.

In the form illustrated seat 14 comprises a strip 30 of longitudinally flexible material, such as cloth, which will accommodate itself to the body of the gunner 22, the strip extending across the body of the user but advantageously limited in width to the width of the gunner's trunk, leaving his arms free to move backward beyond the side margins of the seat. The ends of the strip extend around and are fixed as by rivets to upper cross bar 31 located behind the shoulders or upper back of the gunner 22 and attached to frame 17 by a bracket 32 at each end, and lower cross bar 33 located under the knees of the gunner and supported at each end by a bracket 34 on platform 11. A foot support bar 35 mounted at each end on a bracket 36 fixed to platform 11 may also be provided.

By providing a flexible support 30 for the gunner 22 he is enabled to adjust himself lengthwise in seat 14 to bring his head pivot 19 into accurate alignment with the gun mounting axis 18, a construction which permits gunners of various dimensions to position themselves properly in the indicated manner. However, means for adjusting the seat 14 to take care of variations in the sizes of gunners beyond those which can be accommodated by shifting in the seat

may be provided. In the form illustrated this may be accomplished by mounting the lower cross bar 33 at each end on an eccentric pivot 37 extending through bracket 34, and clamping the bar 33 in adjusted position by means of a clamping nut 38 threaded on an extension of each pivot 37, after the bar 33 has been rotated to adjust the length of strip 30 between bars 31 and 33 to the dimensions of particular gunners.

10 In operating the illustrated type of gun turret the gunner 22 can rotate the turret platform 11 and trunnion members 23 manually or by manipulation of control handle 26, whereby the gun 15 may be pointed in any direction about the horizontal; and the gunner's sighting eye can be maintained in perfect alignment with the sighting device 25 simply by comfortable vertical rocking movements of the gunner's head.

15 The references to horizontal and vertical positions in the specification and claims are not intended as limitations, since the positions of the parts thus described will necessarily vary when they are used on an airplane in flight; but such description is intended simply to designate the relative position of the various parts.

20 I have described what I believe to be the best embodiments of my invention. I do not wish, however, to be confined to the embodiments shown, but what I desire to cover by Letters 25 Patent is set forth in the appended claims.

30 I claim:

1. In combination, a gun turret revoluble about a vertical axis, gun mounting means on the turret defining a horizontal pivotal gun axis in fixed relation to the turret, and a stable, supporting 35 hammock for the gunner mounted on the turret, in which gunners of different sizes may comfortably and stably place themselves lengthwise of the hammock in different semi-reclining positions, respectively, according to their personal requirements, so that the cranial pivot of the gunner in each instance will substantially coincide with said defined horizontal pivotal gun axis.

2. In combination, a gun turret revoluble 40 about a vertical axis, gun mounting means on the turret defining a horizontal pivotal gun axis in fixed relation to the turret, and a hammock-like support for the gunner mounted on the turret, comprising widely spaced, end supports rigidly affixed to the turret and a broad flexible web connected between the supports and having considerably greater length than the distance between the points at which it is connected to the supports, in which gunners of different sizes may 45 comfortably and stably place themselves in different semi-reclining positions, respectively, according to their personal requirements, so that the cranial pivot of the gunner in each instance will substantially coincide with the defined horizontal pivotal gun axis.

3. In combination, a gun turret revoluble 50 about a vertical axis, gun mounting means on the turret defining a horizontal pivotal gun axis in fixed relation to the turret, and a stable, hammock-like support for the gunner mounted on the turret, comprising widely spaced, end supports rigidly affixed to the turret and a broad flexible web connected between the supports and having considerably greater length than the distance between the points at which it is connected to the supports, in which gunners of different sizes may comfortably and stably place themselves in different positions, respectively, according to their personal requirements, so that the cranial pivot of the gunner in each instance will 55 60 65 70 75

substantially coincide with said defined horizontal pivotal gun axis, one of said end supports for the flexible web being located adjacent the gun axis and substantially higher than the other end support, to facilitate the gunner's assuming an attitude in which his trunk is inclined at an angle of the order of 45°.

4. In combination, a gun turret revoluble about a vertical axis, gun mounting means on the turret defining a horizontal pivotal gun axis in fixed relation to the turret, a stable, hammock-like support for the gunner mounted on the turret, comprising widely spaced, end supports rigidly affixed to the turret and a broad flexible web connected between the supports and having considerably greater length than the distance be-

tween the points at which it is connected to the supports, in which gunners of different sizes may comfortably and stably place themselves in different positions, respectively, according to their personal requirements, so that the cranial pivot of the gunner in each instance will substantially coincide with said defined horizontal pivotal gun axis, one of said end supports for the flexible web being located adjacent the gun axis and substantially higher than the other end support, to facilitate the gunner's assuming an attitude in which his trunk is inclined at an angle of the order of 45°, and means for adjusting one of the end supports to adapt the gunner's support for gunners of different size ranges.

JOHN A. VAUGHAN.
